UNITED STATES PATENT OFFICE.

HEINRICH EMANUEL LUDWIG, OF BERNE, SWITZERLAND.

RACK-RAIL FOR MOUNTAIN RAILWAYS.

SPECIFICATION forming part of Letters Patent No. 413,827, dated October 29, 1889.

Application filed May 8, 1889. Serial No. 310,048. (No model.)

To all whom it may concern:

Be it known that I, HEINRICH EMANUEL LUDWIG, a citizen of Switzerland, residing at Berne, Switzerland, have invented new and useful Improvements in Rack-Rails for Mountain Railways, whereof the following is a specification.

My invention relates to the rack-rails of mountain railways, and its object is to render the teeth of the rack-rails stronger, so as to increase the safety of the said railways. For this purpose the rack-rails are made of bars of wrought-iron or steel by a rolling or pressing process, whereby the original surface of the bars is partly raised and partly depressed, so that hollow projections constituting the teeth are formed thereon.

In the annexed drawings, Figure 1 is a longitudinal section of an improved rack-rail, together with a transverse section of a pair of rolls adapted for manufacturing the same. Fig. 2 is a section on line $x y$, Fig. 1.

a is the body of the bar, having flanges *b* for fastening the same on sleepers. *c* are the teeth. The sectional shape of the said bar is, 25 however, unessential, as the teeth may be formed on bars of different shape without departing from the nature of the invention.

I claim as my invention—

A rack-rail consisting in a bar of wrought- 30 iron or steel having hollow projections formed thereon, which are closed at the sides and the top, and which constitute gear-teeth, substantially as described.

In testimony whereof I have hereunto set 35 my hand in the presence of two subscribing witnesses.

HEINRICH EMANUEL LUDWIG.
